CASE STACKER

Roger A. Scott, Kirklin, Ind., assignor to American Utensil Company, a corporation of Illinois

Application February 8, 1940, Serial No. 317,916

4 Claims. (Cl. 198—26)

My invention relates to case stackers or elevating devices and is principally designed for use in cannning plants, warehouses, breweries, dairies and other places where materials in cans, bottles or other containers are usually handled in standard size cases, boxes, cartons or crates. In all such places large quantities of cases, boxes, cartons or crates are usually stored and must be moved in stacking or unstacking or in loading or unloading trucks or cars.

The principal object of the present invention is to provide a case stacker that is an improvement over anything at present on the market.

A further object of the invention is to provide a machine of the type described by having a boom which is automatically adjustable and movable to a desired angle and height.

A further object is to provide a machine of the type described having an improved automatic feed mechanism associated with both the top and bottom ends of the boom so that cases or crates may be fed to the conveyor from either end.

A further object is to provide an improved machine of the type described that is extremely light and capable of easy movement from place to place, yet sufficiently strong and sturdy so that it will withstand long and hard usage without becoming broken or out of order.

A further object is to provide safety means for rigidly securing the boom in a desired raised position so that regardless of the load being elevated the boom will not slip or lower during operation.

Other objects and advantages will be more apparent from the following description wherein reference is had to the accompanying two sheets of drawings, upon which

Fig. 1 is a vertical sectional view through the stacker with the upper end broken away;

Fig. 1a is a continuation of Fig. 1 and shows the upper end of the boom and platform;

Fig. 2 is a side elevation view of the upper end of the stacker and loading platform;

Fig. 3 is a fragmentary sectional view of the same parts showing the adjustment for the belt fastener;

Fig. 4 is an enlarged cross-sectional view showing the belt supporting structure and is taken on the line 4—4 of Fig. 1;

Fig. 5 is a cross-sectional view through the upper carriage showing the automatic feed mechanism associated therewith, and is taken on the lines 5—5 of Fig. 2;

Fig. 6 is an enlarged sectional view through

the upper conveyor belt roller and is taken on the line 6—6 of Fig. 1a;

Fig. 7 is a plan sectional view of the drive and brake mechanism taken generally on the lines 7—7 of Fig. 1;

Fig. 8 is a vertical sectional view through the supporting frame and is taken generally on the lines 8—8 of Fig. 1;

Fig. 9 is a fragmentary sectional view showing the mechanism for controlling the boom elevation, and

Fig. 10 is a cross-sectional view through the lower platform mechanism.

In the embodiment of the invention which I have chosen to illustrate, I have provided a rectangular frame 10 which may be composed of angular irons suitably secured together in the usual manner and supported upon a plurality of roller members 12. The rollers may be universally mounted so that they may be easily directed in any desired direction. The frame 10 may be provided adjacent one end with a pair of upright frame members 14 secured together by a reinforcing angle 16 and the cross-braces 18 and 20. At the forward end of the frame 10 (Fig. 1), I provide a pair of upright standards 22 adapted to support a drive shaft 24 and a roller 26. A pair of angle members 28 and 30 are adapted to be pivotally mounted upon the shaft 24.

The angle members 28 and 30 may form the side frames of a boom 32 which carries a cross-shaft 34 at its upper end that is supported in the take-up bosses 36 and 38. A roller 40 is mounted on said shaft disposed between the side angles 28 and 30. A conveyor belt 42 is adapted to be trained about the rollers 26 and 40. The belt may be provided with rectangularly shaped slat members 44 disposed at regular intervals upon its face so that when the conveyor belt is moving, an object resting against a slat will be moved forward in the direction of movement of the belt. The belt is supported during its forward movement either in an up or down direction upon the side frames 28 and 30 of the boom by a plurality of roller members 46 which are disposed at regular intervals in suitable bracket members 48 attached to the side members 28 and 30.

The boom 32 is provided at its upper end with a work receiving or discharge platform 50 constructed of a pair of angle members 52 and 54 which support a plurality of rollers 56 in suitable bearing members 58 fastened in the inside of the angle members. The platform 50 may be supported at the upper end of the boom by a pair of strap members 60 which extend upwardly

from the side plates of the boom and are fastened to the platform upon a suitable pivot 62. Means for supporting the platform 50 at a desired angular position or to keep the same horizontal in spite of the angle of the boom are provided. They comprise a pair of rigid strap members 64 pivotally secured to opposite sides of the frame members 52 and 54 and extending downwardly therefrom. The member 64 may be provided 10 with a plurality of slots 66 adapted to fasten over suitable pins 68 that are carried by support members 70 which extend downwardly upon opposite sides of the boom 32. With this construction it is a simple matter to adjust the upper carriage to a desired position.

When cases are fed downwardly from the upper carriage 50, it is desired to provide automatic means for preventing them from falling or sliding a distance to strike on the slat members 44. 20 Accordingly, the platform 50 may have a stop member 72 pivotally mounted thereon and provided with an upright portion 74 that in normal position extends upwardly into the path of cases upon the rollers 53 and prevents forward movement of the cases. The member 72 has a further extension 76 extending directly over the belt 42 so that when a slat 44 engages the extension 76 the member 72 is swung about its pivot and the stop 74 is lowered so that a case can move forward over the same and go down the conveyor in engagement with the slat 44. The member 72 is normally held in the position shown by a spring 78 about bolt 78. When moving cases in an upward direction, the stop member 72 may be slid downwardly with the bolt 78 and be removably secured in an inoperative position. A sprocket 79 on the first roller 56 may be driven by a chain from a sprocket 81 on the shaft 34.

To operate the conveyor belt 42 in either direction I provide a reversible motor 80 mounted upon suitable supports on the lower platform 10. The motor 80 may be in driving connection with a suitable gear reduction member 82 that has a cross shaft 84 connected with a sprocket 86. 45 The sprocket 86 is connected by a chain 88 with a sprocket 90 which is in driving connection with the shaft 24. Thus, by operating a switch, the motor 80 will be adapted to drive the conveyor belt 42 either up or down as required by the job 50 to be done.

Means for raising or lowering the boom 32 automatically are also provided. This means may comprise a cable 92 which has one end rigidly connected to a fastener 94 at the upper 55 end of one of the vertical supports 14. The cable 92 may extend downwardly and pass over a plurality of rollers 96 connected below the boom frame formed by the angles 28 and 30. The cable may extend upwardly and pass over a suitable 60 roller 98 fastened by a bracket 100 upon the side of opposite upright 14. The cable may then extend downwardly about a pulley 102 secured to the side of the lower frame 10, about a pulley 104 secured to the bottom of the lower frame 10, and 65 then forward and around a drum 106 which is mounted upon a shaft 108. The shaft 108 may also carry a brake drum 110 and a clutch 112. The clutch may have its face opposing a similar clutch face on a pulley 114 which has a chain 116 70 trained about the same. The chain 116 is in driving connection with a sprocket 118 upon the drive shaft 84. The clutch lever 120 is provided to cause the clutch faces 112 to engage and revolve the winding drum 106 in the direction de- 75 sired.

Thus, when the foot pedal 122 is pressed downwardly, the clutches are engaged and the shaft 108 is revolved. At the same time the brake band 121 is released, permitting the shaft 108 to be revolved. From the above it can be seen that a simple yet efficient brake and boom raising or lowering device has been provided. The operation of the same is obtained by releasing the brake and engaging the clutch members through the manipulation of foot pedal 122. When the foot pedal is released the brake band 121 effectively engages the drum 110 and rigidly holds the boom in the desired raised or lowered position.

As a further means for preventing any accidental dropping of the boom, I have provided a plurality of holes 126 in the upright frame members 14 to receive a cross rod 128 below the boom frame whenever a desired angular position is reached. In this way it is impossible for the boom to drop, even though the cable 92 may be broken or other mechanism become out of order.

The lower feed platform 130 may comprise a pair of side frame members 132 and 134 which are supported at one end upon the cross shaft 24 and at the extended end upon a frame 137 which carries the adjustable supporting rod 135. The platform may be provided with a plurality of sheaves 136 at its front and rear ends, upon which a plurality of V-belts 138 may be trained. The sheaves may be driven by a chain drive from the shaft 24 to the sprocket 24a on the shaft 24b which carries the sheaves 136.

With this construction it can be seen that boxes or other containers may be placed upon the lower platform 130 and they will be moved forward against the conveyor 42 so that the cleats 34 can engage the same and move them upwardly to the top of the boom. The stacker is equally adaptable to moving cases to a high location or for removing the same and moving them down into a car or other desired location.

While I have illustrated and described one form of the invention, it will be apparent to those skilled in the art that changes and modifications may be made in the exact details shown, and I do not wish to be limited in any particular; rather what I desire to secure and protect by Letters Patent of the United States is:

1. Apparatus of the class described comprising a supporting frame, a boom disposed at an angle and pivotally connected to one end of said frame, an endless conveyor disposed thereon, spaced cleats secured to the surface of said conveyor, a horizontal platform adjacent the lower end of said boom, a horizontal platform carried by the upper end of said boom and automatic feed mechanism associated with said upper platform, said mechanism including a box stopping member comprising a pivotally mounted L-shaped unit having one arm extending upwardly in the path of cases upon said upper platform and its other arm extending over the upper end of said endless conveyor in position to be moved about a pivot when a slat on the conveyor engages said arm, whereby the upwardly extending arm of the unit is lowered to permit a case to move from said platform on to said endless conveyor.

2. Apparatus of the class described comprising a supporting frame, a boom disposed at an angle and pivotally connected to one end of said frame, an endless conveyor disposed thereon, spaced cleats secured to the surface of said conveyor, a horizontal platform adjacent the lower end of said boom, power driven means thereon for moving boxes upon said conveyor, a horizontal plat-

form carried by the upper end of said boom and automatic feed mechanism associated with said upper platform, said mechanism including a box stopping member comprising a pivotally mounted L-shaped unit having one arm extending upwardly in the path of cases upon said upper platform and its other arm extending over the upper end of said endless conveyor in position to be moved about a pivot when a slat on the conveyor 5 engages said arm, whereby the upwardly extending arm of the unit is lowered to permit a case to move from said platform on to said endless conveyor, a bolt member for supporting said mechanism, said bolt member capable of movement to move said stopping member out of the 10 path of boxes on said platform or conveyor when it is desired to move cases up on said conveyor to said platform.

3. The combination with a case stacker having a boom disposed at an angle, an endless conveyor disposed thereon, spaced slats on said conveyor and a platform secured to the end of said boom of automatic feed mechanism disposed between said boom and said platform, said mechanism including a stop member pivotally mounted on said platform, said stop member having an upright arm normally extending into the path 15 of cases upon said platform, an angular extension 20

25

sion therefrom positioned over the upper end of said endless conveyor so arranged that when a slat on said conveyor engages said extension, the mechanism is swung about its pivot to lower the stop member and permit a case to move from 5 said platform on to said endless conveyor.

4. The combination with a case stacker having a boom disposed at an angle, an endless conveyor disposed thereon, spaced slats on said conveyor and a platform secured to the end of said boom, of automatic feed mechanism disposed between said boom and said platform, said mechanism including a stop member pivotally mounted on said platform, said stop member having an upright arm normally extending into the path of cases upon said platform, an angular extension therefrom positioned over the upper end of said endless conveyor so arranged that when a slat on said conveyor engages said extension the mechanism is swung about its pivot to lower the 20 stop member and permit a case to move from said platform on to said endless conveyor, said mechanism supported on a bolt member capable of movement to remove said stop member when it is desired to move cases up on said conveyor to 25 said platform.

ROGER A. SCOTT.
